H. F. BLACKBURN AND W. J. CUMMINGS,
OIL DISCHARGE JET,
APPLICATION FILED SEPT. 23, 1921.

1,412,267.

Patented Apr. 11, 1922.

UNITED STATES PATENT OFFICE.

HENRY F. BLACKBURN AND WILLIAM J. CUMMINGS, OF BRECKENRIDGE, TEXAS.

OIL-DISCHARGE JET.

1,412,267.

Specification of Letters Patent. Patented Apr. 11, 1922.

Application filed September 23, 1921. Serial No. 502,785.

To all whom it may concern:

Be it known that we, HENRY F. BLACKBURN and WILLIAM J. CUMMINGS, both citizens of the United States of America, 5 residing at Breckenridge, in the county of Stephens and State of Texas, have invented certain new and useful Improvements in Oil-Discharge Jets, of which the following is a specification.

10 Our invention relates to improvements in jets for discharging oil by means of gas by utilizing the pressure of the natural gas; and the object is to provide a simple jet which will be self acting to lift oil out of 15 wells by utilizing the pressure of the natural gas and another object is to make the gas engage the oil in a direction approximating the direction of the flowing oil which is being discharged so that the flow 20 of oil will not be impeded but pushed upwardly and saving the force of the momentum of the oil. Another object is to provide means for regulating the passage of gas into the oil line so that more or less gas can 25 be let into the oil line and also so that the gas passages can be closed entirely in case of necessity. One advantage of this invention is that no gas or air or steam is necessary for lifting the oil out of the wells and 30 so that pressure on the oil sands by gas or air or steam introduced from the surface of the ground is avoided. Another advantage is that if there is not enough natural 35 gas to lift the oil out of the wells, gas or air or steam may be introduced from the surface for lifting the oil out of the well without pressing on the oil sands. This invention is an improvement shown in the application filed by Henry F. Blackburn and Earl 40 L. McMillen on Sept. 2, 1921, Ser. No. 498,117, for oil discharge jets. Other objects and advantages will be fully explained in the following description and the invention will be more particularly pointed out 45 in the claims.

Reference is had to the accompanying drawings which form a part of this application.

Fig. 1 is a side elevation of the jet without the connections. Fig. 2 is a vertical section of the jetting devices, shown with the connections. Fig. 3 is an inverted plan view of the jet as shown in Fig. 1. Fig. 4 is a similar view to Fig. 3, but omitting 55 the retaining collar and showing in dotted

outline the gas passages and the means for regulating and closing the gas passages.

Similar characters of reference are used to indicate the same parts throughout the several views.

The improved jet includes a body member 1 which has a reduced upper portion 2 for making connections either with a tubular connection 3 or with the collar 4. The collar 4 forms a seat for a plunger barrel. The object of the collar 4 is to support the plunger barrel for starting the flow of oil by pumping where the gas has been covered by water or oil until the gas will not start the oil to flowing. After the oil has been started to flowing through the plunger barrel by means of a pump, the plunger barrel may be removed and the oil will be forced out by the pressure of the natural gas. The collar 4 has a beveled seat 5 for the plunger barrel. The part 2 is also for service as a rope socket neck for fishing out the jet in case of necessity. The jet 1 has a passage 6 for the upward flow of oil. The oil comes through a pipe 7 which may extend down any suitable distance in the oil sands and is perforated for the intake of oil. A sleeve 8 is screwed on the lower end of the jetting devices for collecting the gas about the pipe 7. Openings 9 are made in the body 1 at inclines so that gas may pass through the member 1 somewhat in the direction of the flowing oil so that the gas will be pushing upwardly when it strikes the column of upward flowing oil. Means are provided for regulating the amount of gas that may pass through the openings 9. A sleeve 10 is mounted on the body 1 and is rotatable thereon. The sleeve has a cut out 11 therein and a set screw 12 is inserted in the body 1 so that the rotation of the sleeve will be limited to the length or width of the cut-out 11. The sleeve 10 has openings 13 which are adapted to register with the openings or passages 9. The openings 9 can be partly or entirely closed by rotating the sleeve 10 on the body 1. The sleeve 10 is supported in place by a collar 14 and a set screw 15 which binds the collar 14 to the reduced body portion 16. Considering Fig. 4, when the set screw or lug 12 is at the position *a*, the openings 13 and 9 are both open and registering with each for the passage of gas. When the sleeve is turned so that the lug 12 is in position *b*, the openings 9 are closed. 110

The openings 9 can be opened more or less according to the gas pressure.

If there is no gas pressure which can be used, the openings 9 can be closed and the 5 pump used as other pumps which use gas or air or steam for pumping purposes. The body 1 has a threaded opening 17 for receiving a tube for introducing air or steam or gas from the surface. The collar or 10 sleeve 10 has openings 18 for passage of air, steam, or gas into the oil line. In case it is necessary to use a pumping element from the surface, the collar or sleeve 10 is rotated to close the openings 9 and to open the 15 passages 18. The pumping element will come down the opening 17 and enter the annular space 19 about the body 1 so that the pumping element may enter the oil line radially from several directions. In this 20 operation, there would be no pressure on the oil sands. Instead of introducing the pumping element through opening 17, the pumping element may be introduced through an opening 20 through the sleeve 10 into the 25 annular space 19. There would be no pressure on the oil sands in such operation.

Various changes in the sizes, proportions, and construction of the several parts may be made without departing from our invention.

30 What we claim, is,—

1. A jet for lifting oil from wells through a discharge pipe consisting of a body member having a passage therethrough for oil and interposed between sections of a discharge 35 pipe and having gas ducts leading from the lower end of said body up through portions of said body to said passage, means for collecting gas about the discharge pipe below said body at said ducts, and means for closing or partly closing said ducts.

40 2. A jet for lifting oil from wells through a discharge pipe consisting of a body having a passage therethrough and interposed between sections of the discharge pipe, and 45 having gas ducts leading from the lower end of said body at an incline and terminating in said passage, means for closing or partly closing said gas ducts, means for directing

gas to said gas ducts, and means connected to the upper end of said body for starting the 50 flow of oil.

3. A jet for lifting oil from wells through a discharge pipe having a body provided with an oil passage therethrough and to be interposed between sections of a discharge 55 pipe and provided with gas ducts leading from the exterior inwardly at a slight incline and upwardly, and a sleeve rotatable on the periphery of said body and adapted to close or partly close said gas ducts and 60 having inclined ducts adapted to register with said gas ducts and having an incline in the same direction as the incline as the ducts in said body.

4. A jet for lifting oil from oil wells 65 through a discharge pipe and provided with an oil passage therethrough and to be interposed between sections of a discharge pipe and having an annular shoulder at the upper end thereof, a sleeve rotatably mounted 70 on said body and having inclined gas ducts adapted to register with the ducts in said body, a stud rigid with said body and said sleeve having a cut-out in the upper end to receive said stud for permitting a limited 75 rotation of the sleeve on said body, a collar fixedly mounted on the lower end of said body for supporting said sleeve against said shoulder, and means for collecting gas below said sleeve and body about an oil discharge pipe.

5. A jet for lifting oil from oil wells 80 through a discharge pipe having a body provided with a passage therethrough and having upper and lower ducts leading from the periphery thereof upwardly and inwardly to said passage for a pumping element under force, means for directing a pumping element to said ducts, and a sleeve 85 having a limited rotatable movement on said body for opening or partly opening said lower ducts and for closing said lower ducts.

In testimony whereof, we set our hands this 16th day of September, 1921.

HENRY F. BLACKBURN.
WILLIAM J. CUMMINGS.
